UNITED STATES PATENT OFFICE.

GEORGE CROMPTON, JR., OF WORCESTER, MASSACHUSETTS.

SHUTTLE-DRIVING MECHANISM FOR NARROW-FABRIC LOOMS.

Application filed June 12, 1922. Serial No. 567,720.

To all whom it may concern:

Be it known that I, GEORGE CROMPTON, Jr., a citizen of the United States, residing at Worcester, in the county of Worcester and State of Massachusetts, have invented a new and useful Improvement in Shuttle-Driving Mechanism for Narrow-Fabric Looms, of which the following is a specification.

10 My invention relates to narrow fabric looms, and more particularly to the shuttle drive in the lay or lathe thereof. In the class of looms to which I refer the shuttles are commonly driven by a rack-rod through 15 the medium of pinion gears in the shuttle blocks and a small rack in the lower groove of the shuttle. The drive described is a positive drive. I propose to substitute therefor a frictional drive and at the same 20 time to provide stops in the blocks to properly position the shuttles. In so doing I eliminate the occurrence of broken teeth which almost always entails smashed shuttles, smashed warp and a shutdown for re- 25 pairs.

In the drawings:

Fig. 1 is a general representation of my mechanism, partly in elevation and partly in section.

30 Fig. 2 is a section on the line 2—2 of Fig. 1.

Fig. 3 is an enlarged section of the tension mechanism.

Fig. 4 is a diagrammatic view of the positioning devices.

Fig. 5 is an enlarged back view of one shuttle.

Fig. 6 is an enlarged view of part of a pinion wheel.

40 In the drawings I show at 1 a drive rod, on the top of which is any suitable frictional surface, e. g., rubber, shown at 2. This drive rod is accurately positioned in a vertical direction and is also made to reciprocate with the minimum of friction by means of the rollers 3. Above the drive rod and made to revolve by it are the pinion rollers 4. These rollers may be made of fibre or they may be made of steel and fluted as shown 50 (see Fig. 6).

In the lower groove or sticking of the

shuttles 5 I provide another frictional material 6, preferably the same as that at 2. The top groove or sticking of the shuttles fits in the top blocks 20, as usual, but there 55 is in addition the tension rollers 7. These rollers serve the dual purpose of allowing the shuttles to ride smoothly and at the same time to press them down against the pinions 4. For the latter purpose is provided 60 the tension adjusting mechanism indicated generally by 8, which consists of the forked studholder 9, the collar 10, the set screw 11, the spring 12, the bracket 13, and the nut 14.

In Fig. 4 is diagrammatically indicated 65 how the shuttles are prevented from running over or getting out of alignment. I show in Fig. 4 one representation of the shuttles in their right hand position and one representation of the shuttles in their left hand 70 position. On the back of each shuttle is provided the upper groove 15 and the lower groove 16. Each block has either a lower pin 17 or an upper pin 18, alternate blocks having lower pins and alternate blocks having upper pins as shown. It will now be evident that since the right and left positions of the grooves also alternate, that the shuttles will be stopped when the end of the groove reaches the pin in the respective 80 blocks and that there will be no interference of the pins and grooves at the wrong time or place. Note particularly Fig. 4 showing the two end positions of the shuttles and the 75 positions of the pins 17 and 18.

The shuttles are held in their race ways by means of the lower blocks 19 and the top blocks 20, which are affixed to the lathe 21 by the backs 23. At 22 is shown the reed rail.

85 My mechanism operates as follows: Any suitable shuttle motion is provided to drive the drive rod 1 in precisely the same manner in which the rack rod is driven. I have not shown this mechanism as it may be of any usual or desired kind and is not necessary to the understanding of my invention. Similarly, the rod 1 is provided with stops of any suitable or usual kind (not shown) to limit its movement in either direction. It is desirable in case the loom is to be run fast 100 or to do heavy work to give the rod 1 a

movement about 1% to 2% in excess of the desired movement of the shuttles.

As the drive rod reciprocates it drives the pinion rollers 4 by frictional contact. These in turn drive the shuttles by frictional contact with the surface 6. The shuttles are kept against the pinions by the pressure of the spring 12, which is adjustable as described and which acts through the rollers

7. The shuttles are kept from moving beyond the desired distance by the pins and grooves above described, and in case a shuttle should slip a little on any pick, it would obviously be forced into position again on its return. If the shuttles should slip excessively, the set screw 11 should be tightened.

Instead of going to pieces all of a sudden, my mechanism will gradually wear out, when the frictional surfaces can be replaced, thus saving smashes and shutdowns.

It is obvious that instead of making the top rollers 7 adjustable with spring pressure that I can make them fixed with respect to the top blocks and can make the latter adjustable. I can make the rollers 3 adjustable in a vertical plane, but if they are accurately positioned in the first place this is unnecessary. It is equally obvious that my invention can be applied to the so-called "double-deck" lathe, wherein one set of blocks and shuttles is placed above the other, each weaving a separate set of goods or pieces.

Having thus given an illustrative embodiment of my invention, I wish it understood that although specific terms are employed, they are to be taken in a descriptive or generic sense, the scope of my invention being set forth in the following claims:

40 1. In a loom, a lay, a plurality of shuttles guided in race blocks on said lay, frictional means to drive the said shuttles and stopping means to prevent the shuttles from overrunning in the blocks.

45 2. In a loom, a lay, a series of pairs of blocks spaced apart on the lay, each of said pairs including spaced upper and lower blocks forming a shuttle race therebetween, a friction roller mounted in each lower block with its periphery projecting into said shuttle raceway for frictionally propelling the shuttle, and beyond the lower face of said lower block, and a reciprocable drive rod frictionally contacting all of said rollers for rotating the same, first in one direction and then in the other.

50 3. In a loom, a lay, spaced blocks on said lay, and arranged to form shuttle races, friction rollers disposed on said blocks so as to frictionally contact with the shuttles when in the races to propel the shuttles, and a drive rod reciprocably mounted on the lay in position to contact with said friction rollers to rotate the same first in one direction and then in the other.

4. In a loom, a lay, spaced blocks on said lay and arranged to form shuttle races, friction rollers located on said blocks so as to frictionally contact with the shuttles when in the races to propel the shuttles, means to adjust the frictional contact of said rollers against the shuttle, and a drive rod reciprocably mounted on the lay in position to frictionally contact with said rollers to rotate the same first in one direction and then in the other.

5. In a loom, a lay, a block on said lay comprising spaced members to form a shuttle race, a friction roller disposed on one of said members to frictionally contact with the shuttle when in the race, means to propel said frictional roller in either direction, and a second friction roller disposed on said other member and arranged to press against said shuttle.

6. In a loom, a lay, a block on said lay comprising spaced members to form a shuttle race, a pair of friction rollers carried by one member to frictionally contact with the shuttle when in the race, a second pair of friction rollers adjustably carried by the other member to contact against said shuttle when in the race, and means to propel one pair of said friction rollers.

7. In a loom, a lay, a block on said lay arranged to form a shuttle race, a friction roller disposed on said block, means to press said roller into frictional contact with the shuttle when in the race, and means to rotate said friction roller in either direction to propel said shuttle.

8. In a loom, a lay, a block on said lay and arranged to form a shuttle race, a friction roller disposed on said block so as to frictionally contact with the shuttle when in the race, means to adjust the contact pressure therebetween, and means to rotate said roller in either direction.

9. In a loom, a lay, spaced blocks on said lay arranged to form opposed shuttle races, a shuttle, means to propel said shuttle from one recess into the other, and cooperative means on each block and on said shuttle for positively limiting the movement of said shuttle into either race.

10. In a loom, a lay, a series of spaced blocks on said lay arranged to form pairs of opposed shuttle races, a plurality of shuttles, each arranged to be propelled back and forth into the races of each pair, means to propel said shuttles, a pin on each block, a pair of spaced apart grooves on each shuttle, said pins and grooves being constructed and arranged to positively limit the movement of each shuttle in a race and irrespective of its direction of propulsion.

11. In a loom, a lay, a series of spaced blocks on said lay arranged to form pairs of opposed shuttle races, a plurality of shuttles, each constructed and arranged to be

propelled back and forth into the races of each pair, means to propel said shuttles, means to positively limit the movement of said shuttles in said races, said means comprising upper and lower grooves on said shuttles arranged in the same relation on alternate shuttles and a pin on each block, said pins being arranged alternatively, upper and lower, on said blocks to correspond with the alternative arrangement of the upper and lower planes of the grooves in said shuttles. 10
